UNITED STATES PATENT OFFICE.

FREDERICK W. REINHARDT, OF MONACA, PENNSYLVANIA.

SAND-BLAST APPARATUS.

SPECIFICATION forming part of Letters Patent No. 781,965, dated February 7, 1905.

Application filed June 18, 1904. Serial No. 213,129.

To all whom it may concern:

Be it known that I, FREDERICK W. REINHARDT, a citizen of the United States of America, residing at Monaca, in the county of Beaver and State of Pennsylvania, have invented certain new and useful Improvements in Sand-Blast Apparatus, of which the following is a specification, reference being had therein to the accompanying drawings.

This invention relates to a sand-blast apparatus, and relates in particular to dry-sand-blast apparatus especially adapted for sand-blasting the interior and exterior surfaces of globes, shades, and other hollow articles.

In the preferred manner of carrying my invention into practice I impel the sand against the article to be engraved by air-suction instead of a blast of air—that is, I cause the sand to be drawn into a chamber and driven against the article to be engraved by a draft of air created by suction. It is, however, practicable by the use of my improved apparatus to force the sand against the glass by a blast of air and to utilize the means for creating suction for the purpose of removing the dust that is created during the operation of the apparatus.

My invention consists in the novel construction, combination, and arrangement of parts hereinafter described and claimed.

In the accompanying drawings, wherein like numerals of reference are used to designate similar parts in the several figures, Figure 1 is a side elevation of my improved apparatus. Fig. 2 is a vertical sectional view looking in a direction opposite to that from which Fig. 1 is taken, said view being taken on the line 22 of Fig. 3. Fig. 3 is a top plan view with the lid of the apparatus removed. Fig. 4 is a view similar to Fig. 3, showing a modified form of apparatus which I employ when the exterior surface of articles are to be treated. Figs. 5 and 6 are detail perspective views of parts of the apparatus shown on an enlarged scale; and Fig. 7 is a top plan view, also on an enlarged scale, of another part of the apparatus.

The articles to be treated are during their

treatment placed in a box or casing 1, which is of suitable size and shape and is mounted 50 on legs 23. The casing 1 has a hinged lid 4, and the upper edge of the casing is provided with a bead 5, the upper edge of the casing and the bead being covered by a strip of rubber 6, while a similar strip of rubber 7 is arranged at the edges of the lid, so that the lid will form a tight joint with the upper edge of the casing. Upon the bottom of the box or casing 1 is arranged a conical sand-hopper 8, which is suspended from the box or casing 60 by straps 9, that are hung on pivots 10. The hopper 8 is attached, by a flexible diaphragm 11, to a plate 12, fixed on the bottom of the casing, and a pipe 13 passes through the hopper and up into the casing, projecting a short 65 distance above the bottom thereof, and a similar flexible diaphragm 14 is arranged within the casing and attached to the pipe 13 and the bottom of the casing, so as to provide a flexible attachment between the casing and 70 the pipe and allow of the pipe having a movement relatively to the bottom of the casing. The pipe 13 passes through the bottom of the hopper and extends a short distance below said hopper, and in one operation of 75 the machine the end of this pipe is open, so that air may enter freely, and in another operation of the machine, where a forced draft is to be used to impel the sand, a pipe 15 is connected to the pipe 13 by a union 16, the 80 said pipe 15 leading to a suitable source of supply of air under pressure, such as a fan or pump. The hopper is connected by a pitman 16' with a crank 17 on a shaft 18, that is journaled in suitable bearings 19 and that carries a pulley 20 on its outer end.

Within the casing 1 and held in position against the side thereof by means which will be hereinafter described is a frame, (shown in detail in Fig. 5,) the said frame consisting of 90 slotted arms 21 22 23 24, all formed integral with a central vertical slotted arm 25, and the said frame is sustained in position by means of a shaft 26, which projects through the side of the casing and has a thumb-nut 27 on its 95 inner end. The outer end of the shaft 26 is

2 journalized in a bracket 28, which is fastened to the outside of the frame by bolts 29, and the shaft 26 carries a hand-wheel 30, by means of which the shaft can be turned when desired, 5 so as to swing the frame around in a circular plane, the shaft 26 being squared where it passes through the slot or any of the slots in the said arms of the frame. A flat spring 30' is interposed between the hand-wheel 30 and 10 the bracket 28, the said spring being fixed to the bracket at its center and being adjusted to press more or less strongly at its ends against the outer face of the hand-wheel 30 by adjusting screws 28' and nuts 29'. A slotted bar 31 15 is adjustably held in position against the said frame by means of a bolt 32, which has a squared body adapted to fit in any of the slots in the arms of the frame, and a nut 33, which screws on the bolt 32, serves to hold the bar 31 in any position to which it may be adjusted on the frame. The bar 31 has a projecting arm 34, which has formed on its end a sleeve 35, that receives a shaft 36, which is 20 revoluble in the sleeve and is longitudinally adjustable therein, being held in any desired 25 position in the sleeve by collars 37 37 and set-screws 38 38, passing through these collars. The shaft 36 carries on its outer end a work-holder or chuck 39, which is secured on the 30 shaft by a set-screw 40, and the said work-holder is provided with jaws 41 to sustain an article 42, such as a globe or shade, that is to be treated, and the work-holder or chuck 39 is provided with radial spokes 43, which are 35 engaged by spokes 44, carried by a disk 45, that is fixed to a shaft 46, journaled on the side of the casing 1. The shaft 46 is journaled in the end of a slotted arm 47, which is adjustable in a slotted bracket 48, that is attached 40 to the outside of the casing, the arm and the bracket being held in their adjusted position by a bolt 49 and thumb-nut 50, which bolt passes through the slot in the bracket and the slot in the arm. A number of holes 51 are 45 provided in the casing, so that the shaft 46 can be passed through any one of these holes to secure an adjustment of the disk 45 relatively to the work-holder or chuck 39, those holes which are not in use being plugged during 50 the operation of the apparatus. A pulley 52 is fixed on the outer end of the shaft 46, and by means of said pulley motion can be communicated from a suitable source of power to the said shaft. 55 A suction-pipe 53 is arranged at one side of the casing, being in communication with the interior thereof, and suction is created in this pipe by means of any suitable suction apparatus connected therewith. 60 The operation of the apparatus is as follows: The article to be treated is mounted in the work-holder or chuck 39, and a rotary movement is imparted to the work-holder 65 from the pulley 52, shaft 46, disk 45, and arms 44. Meanwhile suction is applied to the pipe 53, which will draw air through the pipe 13, and the said pipe being provided with holes 13' within the hopper 8 the sand in the hopper will run through the holes and be drawn upwardly and caused to strike the article 42 with sufficient force to effect the desired result in the manner well known in the operation called "sand-blasting." While the sand is being drawn from the hopper in the manner described an oscillating movement is 70 communicated to the hopper by motion imparted to the pulley 20, and the result of the movement of the hopper is that the upper end of the pipe 13 constantly changes its position so as to distribute the sand and direct it to 75 every part of the article being treated. The dust which arises in the interior of the apparatus will be drawn off through the suction-pipe 53, and as the operation proceeds the article 42 is turned around so as to present 80 the different parts of the surface to the sand flowing up through the pipe 13. The work-holder or chuck can be adjusted in position relatively to the upper end of the pipe 13 in a variety of ways. For instance, it may be 85 adjusted longitudinally by loosening the collars 37 37 and moving the shaft 36 in either direction in the sleeve 35 to accomodate a longer or shorter article than that shown in the drawings. The angle of the work-holder 90 to the pipe 13 can be adjusted by swinging the bar 31 around on the bolt 32 as a pivotal point, the portion of the bolt which passes through the slot in the bar 31 being round, while the portion of the bolt which passes 95 through one of the slots in the frame is square. The slot in the bar 31 also permits of the longitudinal movement of the bar on the bolt 32 to secure additional adjustment, and the slots in the various arms allow of the frame being 100 adjusted to a great variety of positions upon the shaft 26, and by turning the shaft 26 through the hand-wheel 30 the frame may be adjusted to any position relatively to the said shaft by swinging it around in a circle, 105 and by this means every portion of the surface of the article may be successively exposed to the action of the sand coming through the pipe 13. 110 The operation of the devices as above described is particularly adapted to the treatment of the interiors of hollow articles; but where the exterior surface of such articles is to be treated I prefer to employ the devices shown in Fig. 4 of the drawings, the other parts of the apparatus being dispensed with during the operation of the devices shown in Fig. 4 and, if desired, removed 115 from the casing 1. The apparatus illustrated in Fig. 4 comprises a screw 54, which passes 120 through a screw-threaded bearing 55, mount-

ed on the end of the casing, said screw carrying on its outer end a pulley 56 and an adjustable crank-handle 57. The inner end of the screw 54 carries a shaft 58, and on this shaft are mounted two chucks or work-holders 59 60, said work-holders serving to sustain two articles 61 62 in the position shown in the drawing. Where the parts are arranged in this position, the sand coming through the pipe 13 will impinge against the exterior surface of the articles 61 62, and the said articles being revolved and at the same time moved longitudinally by motion imparted to the screw 54, either through the pulley 56 or the crank-handle 57, every portion of the exterior surface of the two articles will be successively brought into proximity to the upper end of the pipe 13 and will be subjected to the direct action of the sand flowing therethrough.

As hereinbefore mentioned, the manner of causing the sand being drawn through the pipe 13 to impinge against the article being treated may be varied and instead of causing the sand to be drawn up through the pipe 13 solely by suction applied to the suction-pipe 53 the air-pipe 15 may be connected to the lower end of the pipe 13 and a blast of air driven from the pipe 15 upwardly through the pipe 13, thereby forcing the sand through the pipe and into the casing instead of drawing it up solely by suction from the suction-pipe 53. When the last-named method of impelling the sand is employed, the suction from the suction-pipe serves solely to remove the dust from the interior of the casing, the operation of the devices for turning the article being treated being the same in both cases.

Having described my invention, I claim—
1. In a device of the type set forth, the combination of a casing, a sand-receptacle arranged below said casing, a pipe passing through said sand-receptacle and into said casing, means for sustaining an article within the casing, means for projecting sand through said pipe into said casing, and means for maintaining the sand-receptacle in motion while the sand is being projected through the said pipe.

2. In a device of the type set forth, the combination of a casing, a sand-receptacle, a flexible diaphragm connecting said sand-receptacle to the casing, a sand-pipe passing through said receptacle into said casing, means for sustaining an article within the casing in position to be acted on by the sand passing through said pipe, and means for imparting movement to the said sand-receptacle.

3. In a device of the type set forth, the combination of a casing, a sand-delivery pipe entering said casing, means for projecting sand through said pipe and into the casing, a

frame having a plurality of intersecting slots, a shaft adapted to be fixed in any of the slots, 65 said shaft being journaled in the side of the casing, means for turning said shaft to swing the frame, a work-holding chuck adjustably secured on said frame, and means for revolving said chuck.

4. In a device of the type set forth, a casing, a sand-hopper attached to said casing, a sand-pipe passing into said hopper and into the casing, a work-holder or chuck revolvably mounted in the casing, said work-holder or chuck 75 being provided with radial arms, radial arms engaging the radial arms of the said chuck, a shaft on which the radial arms engaging the radial arms of the chuck are carried, a slotted arm in which said shaft is journaled, a slotted bracket adapted to sustain said slotted arm, and means for maintaining the said arm in adjusted position on said bracket.

5. In a sand-blast apparatus, the combination of a casing, a receptacle arranged below 85 the same and adapted to hold sand, a pipe passing into said casing and into said receptacle, means for sustaining an article in proximity to the end of said pipe, and means for creating a vacuum in the casing so as to suck 90 the sand through said pipe and impel it against the article to be operated on.

6. In a sand-blast apparatus, the combination of a casing, a receptacle arranged below the same and adapted to hold sand, a pipe 95 passing into said casing and into said receptacle, means for sustaining an article in proximity to the end of said pipe, means for rotating said article, and means for creating a vacuum in the casing so as to suck the sand through 100 said pipe and impel it against the article to be operated on.

7. In a sand-blast apparatus, the combination of a casing, a receptacle arranged below the same and adapted to hold sand, a pipe 105 passing into said casing and into said receptacle, means for sustaining an article in proximity to the end of said pipe, means for rotating the said article, means for swinging the article in the arc of a circle, and means for 110 creating a vacuum in the casing so as to suck the sand into the same and impel it against the article to be operated on.

8. In a device of the type set forth, a casing and a receptacle arranged therebelow, a vertical pipe having its lower end in communication with said receptacle and its upper end opening into said casing, means for supporting the work, and means in communication with the casing for creating a partial vacuum 115 therein and in said pipe to force the material in the receptacle up through the pipe.

9. In a device of the type set forth, a casing and a receptacle, a pipe establishing communication between the same, means for supporting the work in proximity to said pipe

and means for creating a partial vacuum in the casing and in said pipe to project the material in the receptacle against the work.

10. In a machine of the type set forth, a casing having means for supporting the work, a receptacle and a pipe communicating with the casing and receptacle, and means for creating a partial vacuum in the pipe to project the

material in said receptacle against said work by means of said pipe.

In testimony whereof I affix my signature in the presence of two witnesses.

FREDERICK W. REINHARDT.
